(57) **CLAIM**

The ornamental design for a tilt truck carriage, as shown and described.

DESCRIPTION

FIG. 1 is a top rear perspective view of the tilt truck carriage of the present invention;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a bottom right perspective view thereof; and,

FIG. 9 is another bottom perspective view in use with a container.

The broken lines showing four wheels in FIGS. 1 through 9 are included for the purpose of illustrating portions of the tilt truck carriage and form no part of the claimed design. The broken line showing of a container in FIG. 9 is included for the purpose of illustrating environment and forms no part of the claimed design.
